UNITED STATES PATENT OFFICE.

EDGAR GUY PERKINS, OF FETTERS SPRINGS, CALIFORNIA.

BALL-GAME TARGET.

Application filed April 28, 1927. Serial No. 187,183.

My invention relates to improvements in ball game targets in which the thrown balls are caught and held in a spring wire basket; and the objects of my invention are, first, to provide a novel target for thrown balls, second, to provide a way to release the balls from the target without the necessity of the operator or player to run to and from the target to remove the ball by hand and, third, to provide a quick way of removing the target when broken.

I attain these objects by the mechanism illustrated in the accompanying drawings, in which Figure I is a front view of the entire machine and Figure II a rear view of the same. Similar numerals refer to similar parts throughout both views. Plate I is a front view of the target which is made of metal throughout and consists of an upright square rod 2 to which are attached with hinges 6 two half circular wings 3 in which are set six spring steel finger wires 5 bending convexly outward so as to form a basket a little larger than the diameter of the balls used in the game. A coil spring 4 is attached to the two middle finger wires 5 on the two wings 3. When the operator of the game wishes to release the ball he pulls a cord 8 (shown on Plate II) which is attached to the two ends of the coil spring 4 and finger wires 5 on the two wings 3 and which

cord 8 extends downwardly through the guide ring 7 at the bottom of the upright rod 2 and by pulling on this cord 8 the two circular wings 3 bend backwards opening the basket and releasing the ball which drops on an inclined floor and rolls to the hand of the player. At the top of upright rod 2 is a male member so formed as to fit in a socket or female member of any piece of strap iron used to hang the target on and the male and female parts are fastened together by a bolt 1.

Plate II is a rear view of the target and shows the hinges 6, the cord 8 and the guide ring 7 through which the cords 8 are attached to the end of the spring 4.

I claim:

In combination a target comprising a metal disc receiving member suitably shaped and supported having holes therein from which project wires bent so as to firmly hold a ball tossed between them; said metal disc being constructed in three parts and hinged together so that by pulling on a cord attached to the under part of the two hinged sides of the target the tension of a spring attached to the upper part of the disc will be overcome and the hinged sides bend backward releasing the ball from the grip of the said wires.

EDGAR GUY PERKINS.
